UNITED STATES PATENT OFFICE.

GEORGE A. MEACHAM, OF NEW YORK, N. Y.

IMPROVEMENT IN SUSPENDER-FASTENINGS.

Specification forming part of Letters Patent No. **36,100**, dated August 5, 1862.

To all whom it may concern:

Be it known that I, GEORGE A. MEACHAM, of the city, county, and State of New York, have invented a certain new and valuable Improvement in Attaching Suspenders to Pantaloons, applicable also to other purposes; and I do hereby declare that the following specification, taken in connection with the accompanying drawings, is a full and exact description thereof, prepared for the purpose of procuring a patent thereon.

My invention is a peculiar construction of clasp for clasping the waistband of the pantaloons and supporting them without the aid of the buttons usually employed, the clasp being so constructed that while the hold upon the cloth is very firm, the direction of the strain may be varied at a considerable angle without tending to abrade the cloth or to loosen the hold thereon, thereby adapting the fastening to the movements of the wearer and enabling it to be attached to any desired part of the waistband without requiring any special care as to the direction in which the strain is to fall, the clasp adjusting itself to the proper position. This quality of allowing the suspenders to be attached to any point of the waistband is a very valuable one, as a slight change in the position of the point of suspension will sometimes make considerable difference in the set of a pair of pantaloons, and by my invention this change may be made with ease and facility.

By another peculiarity in the construction of my improved clasp it is adapted to a considerable variation in the thickness of the article clamped therein, whereby it is capable of application to thick and thin pants, and may also be made to support the drawers and pants both together, if desired.

To enable others skilled in the art to make and use my invention, I will proceed to describe its construction and operation by the aid of the drawings, in which—

Figure 1 is a side view of the clasp with a portion of the waistband. Fig. 2 is an edge view of the same. Fig. 3 is a section of a portion showing one manner in which I propose to construct the clasp, and Figs. 4 and 5 are

cross-sections showing the manner in which the band is shifted for thick or thin goods.

The same letters of reference indicate like parts in all the figures.

A A is a strip of metal bent into the form represented, so as to tend by its elasticity to spring open in an obvious manner. I prefer to make this part of my clasp of sheet metal, corrugated, as represented, to give the required stiffness to the legs, while the bend is left plain to allow it to spring readily. At each end of A, I attach a button or washer, B, by a rivet, b, so that it is free to turn upon the said rivet relatively to A, as shown in red lines in Fig. 1. These buttons or washers may be serrated, as represented, to cause them to hold the cloth more firmly; but this is not essential. I prefer them struck up in a concave form, as represented, and the rivet may be dispensed with, a portion of the metal of B serving the purpose thereof, as shown in Fig. 3.

The sides of A are serrated or notched, and a band, C, provided to slip thereon and confine the clasp in a manner common to articles of this character. I construct the band C, however, of an oblong form, as shown in Figs. 4 and 5, and capable of being turned, so as to confine the buttons B at a greater or less distance apart. By means of this band C, and the ordinary adjustment due to the inclined position of the sides of A, I am enabled to adjust the distance between the buttons B and the strain thereon to suit all the variations in the thickness of the goods which occur in practice.

The clamp, as here described, or two or more of them, are attached by means of a ring, D, to the suspenders, and the operation of attaching them to the pants is too obvious to require further description. The clasp may be connected to the suspenders by means of a hook, if desired, to avoid the necessity of detaching the clasp when undressing, the latter remaining on the waistband.

It will be observed that whatever changes may be induced in the direction of the strain upon A, by reason of the motion of the wearer or other cause, the relation between the cloth and the buttons B remains the same, and the

former is subjected to no abrasion by such motion. Were the connection of the clasp to the cloth rigid, the variations in the strain, which are constantly occurring, would soon loosen the hold of the clasp or tear the cloth.

Having now fully described my said invention, what I claim as new therein, and desire to secure by Letters Patent, is—

1. The employment, in clasps, of the buttons B, or their equivalents, so arranged as to allow

the supporting part A to rotate or turn relatively thereto, substantially as and for the purpose herein described.

2. The oblong band C, in combination with the clasp A, substantially as and for the purpose herein set forth.

GEO. A. MEACHAM.
